(57) **CLAIM**

The ornamental design for a dispenser tip, as shown and described.

DESCRIPTION

FIG. 1 is a front perspective of a dispenser tip according to the inventive design;

FIG. 2 is an enlarged front perspective view thereof;

FIG. 3 is an enlarged rear perspective view thereof;

FIG. 4 is a front elevation view thereof;

FIG. 5 is a rear elevation view thereof;

FIG. 6 is a left side elevation (the right side being a mirror image); and,

FIG. 7 is a top plan view.

In all views, a cylinder in which dispenser tip is received is shown in phantom outline not being part of the inventive design and a part of the piston located within the cylinder is also shown in phantom outline in FIGS. 1-3 & 7, not being part of the inventive design.

1 Claim, 4 Drawing Sheets
